UNITED STATES PATENT OFFICE.

JAMES M. HOWE, OF CLEVELAND HEIGHTS, OHIO, ASSIGNOR TO THE S. W. H. ENGINEERING COMPANY, OF CLEVELAND, OHIO, A COPARTNERSHIP.

TRACTOR.

1,347,163.

Specification of Letters Patent.

Patented July 20, 1920.

Application filed November 20, 1918. Serial No. 263,322.

To all whom it may concern:

Be it known that I, JAMES M. HOWE, a citizen of the United States, residing at Cleveland Heights, in the county of Cuyahoga and State of Ohio, have invented a certain new and useful Improvement in Tractors, of which the following is a full, clear, and exact description, reference being had to the accompanying drawings.

This invention relates to a tractor adapted to haul various trailers, farm implements, etc. The invention is particularly concerned with the frame of the tractor, which, while being light and cheap, is very strong and stiff and forms in effect a cantaliver pivoted at the rear or driving axle and adapted, if necessary, to support the entire weight in front of such axle. To this end I have provided a rear housing for the transmission and differential gearing and having suitable axle sleeves, this housing being preferably a casting, and a separate forward extension secured directly thereto and carrying the engine. This forward extension is of pressed metal construction having as its rear end a bulk head which abuts and is removably connected to the forward end of the gearing housing. By this means I cheapen and lighten the frame, and am enabled to provide unusual accessibility for the various mechanisms carried.

The above mentioned features, and others of advantage, will be apparent from the illustrative embodiment of my invention shown in the drawings, and the detailed description thereof hereinafter given. The essential novel characteristics of the invention are summarized in the claims.

In the drawings, Figure 1 is a plan of my tractor; Fig. 2 is a side elevation thereof; Fig. 3 is a sectional plan of a portion of the gear housing and the extension frame, being on a larger scale than Figs. 1 or 2; Fig. 4 is a vertical section of the frame parts shown in Fig. 3; Fig. 5 is a rear end elevation of the extension frame; Fig. 6 is a plan of the extension frame and Fig. 7 is a side elevation of the same, these views being intermediately broken away; Fig. 8 is a plan of the gearing housing and Fig. 9 is a front end elevation of the same looking toward the rear.

Referring first to Figs. 1 and 2, 10 indicates the rear or gear housing, 11 the axle housings secured to its opposite sides, 12 the

pressed metal front extension of the frame 55 abutting and secured to the front end of the gear housing. 13 indicates the rear wheels, the axles of which, not shown, extend through the housings 11 into the gear frame 10 and are there connected through the differential and transmission mechanisms with the propeller shaft 15. This shaft is connected by a flexible coupling 16 with the intermediate shaft 17, which is connected by a clutch 18 with the fly wheel 19 on the engine 65 shaft. 20 indicates the engine which has lateral arms 23 mounted on brackets 22 carried by the extension frame 12.

The front axle 24 is secured to this extension frame 12 by a transverse leaf spring, 29. 70 25 indicates the front wheels, shown as connected by knuckles with the axle, and 26 and 27 and 28 the steering gear (intermediately broken away from Fig. 1), leading from the steering knuckles to the steering 75 wheel. 80 indicates brace rods leading from the front axle to a ball and socket joint 31 carried by the extension frame. 32 designates the hood over the engine, 33 the tank for fuel at the rear of this hood, and 34 the 80 seat for the driver. Suitable controlling levers, not shown, are intended to be within easy access from this seat. The drawings show at 35 a belt pulley which may be clutched with the engine and serve to drive 85 any desired machinery when the tractor is stationary.

Referring now more particularly to Figs. 3 to 9 inclusive, showing the frame in detail, the body of the casing 10 is a box-like member (preferably a single integral casting) 90 having side walls 40 and 41, a front wall 42, rear wall 43 and a bottom 44. This casting has on its side walls suitable bosses as 45 and 46 for transverse shafts, external seats 47 95 for securing the axle housing, internal seats as 48 for carrying the transmission gearing, and suitable transverse stiffening ribs 49. There is also a seat 50 (Fig. 9) at the forward end for attachment of the housing 52 100 which carries the bearing for the propeller shaft.

It will be seen that the rear housing described is a self contained structure carrying the differential gearing, the transmission gearing and the gearing to the pulley 105 35. The gearing itself is not shown. The parts within this rear frame are covered by

removable cover plates 55 and 56 which provide ready access to the interior. The cover plate 56 carries housings 53 and 54 for the shifting mechanisms for the transmission and pulley gearing.

The forward end of the gear housing 10 is formed with bosses 58 presenting seats for the rear end of the extension frame, as shown in Figs. 3, 4 and 9. The extension frame is shown individually in Figs. 5, 6 and 7. It is a pressed metal member having channel shaped sides 60 and 61, a channel shaped front 62, and a rear end bulk head composed of one or more plates 63, 64. This bulk head is effectively secured to the forward end of the gear housing 10. As shown the securing is effected by cap screws 75 passing through the bulk head into the bosses 58 on the forward face of the front wall 42 of the gear housing.

As shown, the bulk head comprises two transverse plates riveted together, the plate 63 being flanged at its ends as shown at 71 and 72 and there riveted to the webs of the side members 60 and 61, and having top and bottom flanges 69 and 70. Suitable gussets 65 are riveted to the top flanges 66 of the side members 60 and 61 and to the top flange 69 on the plate 63. Intermediate gussets 68 are also provided between the plate 64 and the webs of the side beams 60 and 61.

The forward frame is further transversely braced by a sheet metal downwardly-facing trough-like member 80 which is bowed downwardly and carries adjacent to the center a pivot 81 for the forward spring. This member has its end portions outwardly flanged against the webs of the beams 60 and 61 as shown at 83. 84 are gusset plates riveted to the beam 80 and the flanges 66. Near the rear end of the forward frame is a transverse channel shaped brace 86 (the top flange 85 of which is centrally depressed to clear rotating parts). This brace is flanged at its ends and is riveted to the webs of the side members 60 and 61. A suitable bottom plate 87 extends between the brace 86 to the bulk head, being secured to a flange 88 at the lower edge of the brace and to the flange 70.

It will be seen that the forward frame member is a self-contained structure made of sheet metal and thus light but strong and stiff. Though readily disconnectible from the gear housing it constitutes in practice a rigid extension thereof, adapted to effectively support all of the weight upon it, as well as the axle and front wheels when the forward end of the machine tends to lift from the ground.

As heretofore stated the engine is mounted on brackets 22 carried by the front frame. These brackets are shown as sheet metal stirrups having top portions 90, and downwardly extending arms with lateral projec-

tions 91 therefrom which lie beneath the channel flanges 66 and are flanged at their ends at 92, whereby they abut and are riveted to the webs of the channels 60 and 61. The lateral projections 91 also have their upper edges flanged over, as illustrated at 94, these flanged portions extending beneath and being riveted to the channel flanges 66. There being two pairs of these stirrups, four points of support are provided for the engine, which is shown as having its laterally extending arms 23 resting on and secured to these four stirrups.

As heretofore stated the cross beam or bolster 80 carries the seat for the forward spring, beneath which is the axle 24. This axle 24 has holes through it, enabling the securing to the axle of the forward ends of the diagonal brace rods 30. The rear ends of these rods join in a fitting 96 which has on its rear end a ball occupying the socket casing 31 heretofore mentioned, which is secured to the cross member 86. The cross bar 86 is further braced to take the thrust from these brace rods by means of the channel shaped trough member 98 riveted to the channel bar 86 and to the bulk head plates 63 and 64.

The front frame it will be seen, is not only strong, stiff and light, but it is largely open to allow convenient access to all of the parts. One of the advantages with my construction is the ease of accessibility. The tank is made readily removable and when it is taken off it exposes the steering gearing, the coupling and the clutch, and these units may be removed without disturbing the motor or necessitating jacks under the frame. The removal of the top plates of the gear housing exposes the differential and transmission gears. By simply abutting the front frame against the rear frame and bolting it thereto, I provide ready separability enabling the machine to be conveniently taken apart for shipping or repairs.

Having thus described my invention what I claim is:—

1. In a tractor, a running frame consisting of a rear member housing the gearing and a forward extension member carrying the engine and secured independently of the engine frame directly to the front end of the rear member, whereby the engine may be removed from the running frame without dismembering said frame.

2. In a tractor, the combination, with front and rear wheels, of a running frame forming the connection between the front and rear wheels and comprising a rear box-like casting, a sheet metal forward extension directly secured to said casting, and a motor carried by the forward extension and having its frame independent of the connection between the forward extension and the casting.

3. In a tractor, a frame comprising a gear

- housing supported by the rear wheels and a forward extension having as its rear end a bulk head across the front end of the gear housing and secured directly thereto, and 5 an engine removably supported by said extension independently of said bulk head.
4. In a tractor, the combination, with the wheels, of a running frame, comprising a casing for the differential and transmission, 10 and a forward extension for the engine and front axle secured to the front end of said casing, said extension having pressed metal sides and having a bulk head across its rear end, which bulk head abuts and is secured 15 to the front end of the gear casing, and an engine supported by said extension and removable independent of said bulk head.
5. In a tractor, the combination, with front and rear wheels, of a running frame 20 carrying housings for the rear live axle sections and the gearing and connected to the front axle, said frame comprising a box-like casing adapted to contain the gearing, lateral housings for the live axle sections, 25 and a sheet metal forward extension adapted to carry the motor and secured to said box-like frame independently of the motor.
6. In a tractor, the combination of a casting 30 constituting the casing for the differential and transmission, housings for the live axle sections secured to opposite sides of said casting, and a pressed metal forward extension comprising channel-shaped side beams, cross braces and a rear bulk head, said bulk 35 head abutting and being directly secured to the front end of the casting, an engine carried by the forward extension independently of the bulk head, and a clutch between the engine and the bulk head.
- 40 7. In a tractor, the combination of a casting constituting the casing for the differential and transmission, housings for the live axle sections secured to opposite sides of said casting, and a forward extension comprising side beams, cross braces and a rear bulk head, said bulk head abutting and being directly secured to the front end of the casting, and having its side members forming substantially a continuation of the sides 45 of the casting, and reinforcements connecting the bulk head with such side members, and an engine carried by said forward extension independently of the bulk head.
- 50 8. In a tractor, a frame comprising a casting for the differential, housings for the live axles secured to the opposite sides of said casting, a pair of channel beams with their flanges facing inwardly and connected at the rear end by a bulk head, thus providing 55 an open front extension of the frame, said extension abutting the end of the casting and secured thereto, means connected with the bulk head and the side members for stiffening the bulk head, brackets secured to 60 the channel beams and an engine supported

on said brackets and spaced from the bulk head, and a clutch between the engine and the bulk head.

9. In a tractor, the combination of a frame comprising a rear casing for the differential and transmission and housings for the live axle sections, a forward extension of the frame directly connected with said casing, said forward extension having sheet metal side beams and a cross brace, a front 70 axle connected with the extension frame, brace rods leading rearward from said axle, and a seat for the rear ends of the brace rods carried by said cross brace.

10. The combination, with the rear wheels 80 and live axle sections, of a housing for the differential, housings on the opposite sides of the gear housing and containing said live axle sections, said gear housing having side walls, a front wall and a bottom inclining 85 forwardly toward the front, and a front extension frame carrying the engine and connected with the front axle, said extension frame having side walls adapted to register with the side walls of the gear casing and 90 having their lower edges continuing the incline of the bottom of the gear casing.

11. The combination, with the rear wheels and live axle sections of a running frame cantalivered about the rear wheel axis and 95 comprising a housing for the differential, housings on the opposite sides thereof for the live axle sections, and a front extension, said gear housing having side walls, a front wall and a bottom inclining forwardly to- 100 ward the front, and the front extension frame carrying the engine and connected with the front axle, said extension frame having a rear end abutting the front end of the gear housing and having laterally 105 spaced sill members the sides of which register with the side walls of the gear casing, said side members of the extension frame being inwardly facing channels having their top flanges horizontal and their lower 110 flanges inclining forwardly toward the front of the machine.

12. In a tractor, a running frame comprising a rear member housing the gearing and a forward extension member carrying the 115 motor and secured to the rear member independently of the motor frame, whereby said forward extension member may be disjoined from said rear member at a point remote from said motor frame.

13. In a tractor, a running frame consisting of two parts comprising a rear casting housing the gearing, and a forward sheet metal extension member carrying the engine and secured independently of the engine 125 frame to said casting.

14. In a tractor, the combination of a running frame comprising a rear box-like member adapted to house the gearing and a forward extension secured to the box-like mem- 130

ber, said extension having side members spaced apart, an engine supported by the extension some distance in front of the box-like member, and a clutch in the open space 5 within the side members of the front extension and between the engine and box-like member, which clutch can be removed without disturbing the engine or the connection between the forward extension and the gear 10 housing.

15. In a tractor, the combination of a running frame comprising a rear box-like mem-

ber adapted to house the gearing and carrying on its forward end a bearing for the propeller shaft, and a forward extension secured to the box-like member, an engine supported by the extension some distance in front of the box-like member, and independently of it, a clutch, and a separable coupling between the clutch and the propeller shaft. 15

In testimony whereof I hereunto affix my signature.

JAMES M. HOWE.
